Hickok Manufacturing Company, Inc., Rochester, N. Y., a corporation of New York

Application January 30, 1936, Serial No. 60,905

Term of patent 3½ years

To all whom it may concern:

Be it known that I, Daniel T. Manning, a citizen of the United States, residing at Rochester, in the county of Monroe and State of New York, have invented a new, original, and ornamental Design for Belt for Personal Wear, of which the following is a specification, reference being had to the accompanying drawing, forming part thereof.

Fig. 1 is a perspective view of a belt for personal wear, the detailed illustration of the body of the belt being continued throughout the length of the belt, the shaded lines denoting contrasting color; and

Fig. 2 is the under end view of a portion of the belt shown in Fig. 1 on an enlarged scale.

The dominant feature of the present design resides in the ornamental belt having one apertured spatulate buckle carrying end and at its other end a longitudinal series of spaced apart open loop members to receive a portion of the buckle.

I claim:

The ornamental design for belt for personal wear, as shown and described.
